CLAIM

The ornamental design for a retail display, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top front right view of a retail display showing the claimed design;

FIG. 2 is a front view thereof;

FIG. 3 is a top front right view of another retail display showing the claimed design;

FIG. 4 is a front view thereof;

FIG. 5 is a top front right view of another retail display showing the claimed design; and,

FIG. 6 is a front view thereof.

Portions of the retail display that are not shown form no part of the claimed design.

The appearances of the central rectangular surfaces with grid lines in FIGS. 1-6 form no part of the claimed design.

1 Claim, 6 Drawing Sheets

(6 of 6 Drawing Sheet(s) Filed in Color)
